[57] CLAIM

The ornamental design for jeans, substantially as shown and described.

DESCRIPTION

FIG. 1 is a rear and left side perspective view of jeans showing my new design, the broken line matter being for illustrative purposes only and forming no part of the claimed design;

FIG. 2 is a front and right side perspective view thereof; and

FIG. 3 is a left side elevational view thereof.

FIG. 1

FIG. 3
